UNITED STATES PATENT OFFICE.

NORMAN W. PEEK, OF MILWAUKEE, WISCONSIN.

FOOT ACCELERATOR.

Application filed October 7, 1922. Serial No. 593,044.

To all whom it may concern:

Be it known that I, NORMAN W. PEEK, a citizen of the United States, residing at 528 Bellevue Place, Milwaukee, in the county of 5 Milwaukee and State of Wisconsin, have invented certain new and useful Improvements in Foot Accelerators, of which the following is a specification.

The invention relates to foot accelerator 10 for use in controlling the throttle valve of automobiles, and the object is to provide a foot operated accelerator of such a nature that the customary strain on the leg and foot of the driver is eliminated. A further 15 object is providing a device which will be operated by lateral movements of the foot, and one which may be operated positively to close as well as to open the throttle valve. A further object is to 20 provide a device of this character which is simple in construction and which may be quickly installed in any automobile. Other objects and advantages of my invention will appear in connection with the detailed description thereof, and in the claims.

In the drawings which illustrate the application of my invention in one form,—

Figure 1, is a perspective view of the accelerator mounted upon the toe-board of an 30 automobile.

Figure 2, is side elevation view of the accelerator.

Mounted upon the toe-board 1 of the automobile is a wedge shaped block 2, in 35 which is a transverse slot 3. Seated upon the block 2 is a foot operated block 4, having an upper horizontal surface 5, upon which the foot of the operator rests, side projections 6 and 7 being provided to prevent the foot from slipping off of the block 4. Projecting downwardly from the block 4, and integral therewith is a tongue 8, which is guided in the slot 3 of the wedge shaped block 2. Tongue 8 is pivotally connected to a rod 9 which extends downwardly and laterally and is connected by means of a suitable ball and socket connection 10, to a rod 11, mounted upon a cross shaft 12. Cross shaft 12 is mounted in suitable 50 brackets 13 below the toe-board of the automobile, and is provided with an arm 14, which is connected in any suitable manner to the throttle valve of the carburetor. A comparatively light spring 15 is connected 55 to rod 9 at one end, and at the other end is connected to the under surface of the toe-

board of the machine, and serves to maintain the foot piece at its upper and left hand position, which corresponds to the closed position of the throttle valve. 60

It will be seen that the foot piece is operated by a side-wise movement of the foot to open or close the throttle valve. The foot piece 5, will move downwardly and to the right thus operating the shaft 12, and consequently the throttle valve, when the operator desires to open the throttle and accelerate the machine. At any point in its movement the weight of the foot and leg of the operator may be rested on the foot piece 70 in order to relieve any muscular strain of the operator when the car is moving at the desired rate of speed, as the angle of the upper surface of the block 2 will be made small enough so that a downward pressure 75 on the foot piece will not cause the foot piece to move laterally.

If desired, the foot piece 5 may be moved over to its right hand position, and the spring 15 will elevate the same if there is 80 no downward pressure exerted by the foot, and the block 5 may then be operated by vertical pressure of the foot so as to move the same up and down in order to control the throttle in the customary manner. 85

I claim:

1. In a device of the class described, a foot operated member for operating a part to be controlled, adapted to be moved by a foot of the operator, and means for guiding 90 and supporting said member so that the same moves in a laterally inclined plane.

2. A foot operated device of the class described, comprising a foot operated member for operating a part to be controlled, means 95 for guiding said member so that the same moves laterally in an inclined plane, whereby a substantial part of the weight of the foot may be rested on the foot operated member without operation of the part controlled. 100

3. In a foot accelerator for motor vehicles, a foot piece for operating the carburetor control; means connecting said foot piece to the carburetor control, a wedge shaped lock, adapted to be mounted on the toe-board of the motor vehicle, and to support said foot piece, and guide means formed in said block for guiding the foot piece in a substantially lateral direction. 105

In testimony whereof I affix my signature.

NORMAN W. PEEK.
